United States Patent Office.

GEORGE W. LORE, OF DEXTER, MICHIGAN.

Letters Patent No. 98,873, dated January 18, 1870.

STOVE-PIPE DRUM.

The Schedule referred to in these Letters Patent and making part of the same.

To whom it may concern:

Be it known that I, GEORGE W. LORE, of Dexter, in the county of Washtenaw, and State of Michigan, have invented a new and useful Improvement in Heat-Radiating Stove-Drums; and I do declare that the following is a true and accurate description thereof, reference being had to the accompanying drawings, and to the letters of reference marked thereon, and being a part of this specification, in which—

Figure 1 is a vertical section of my improvement, and

Figure 2 is a perspective of the inner shell and deflectors.

Like letters indicate like parts in each figure.

The nature of this invention relates to an improved construction of heat-radiators or drums, through which smoke and gases of combustion pass from the stove to the chimney.

It consists in a rectangular casing, into which the stove-pipe leads, and from the upper part of which it is led. Within the case is another shell, through which the smoke may pass direct, if desired, or ascend in alternating currents between the inner and outer shells, by the arrangement of certain deflecting-plates on the exterior of the inner shell, which deflect it toward the outer or radiating-case, while retaining it in its passage, to allow the heat to be taken up by said casing, and radiated into the apartment in which it is placed; also, in the arrangement and method of operating the valve within the case, for directing and regulating the course of the heated currents through the same.

In the drawings—

A represents a rectangular sheet-metal case or radiator, into which the smoke and heated currents enter through the induction-pipe *a*, and whence they are discharged, through a similar pipe, *b*, at the top, into the stove-pipe proper.

B is a rectangular shell, of sheet-metal, of lesser size than the case A, into which it is inserted. In the upper part of the shell is hung or pivoted a butterfly-valve, C, which is employed to open or close the shell to the passage of the heated currents through the same, having attached to it a lever, *c*, projecting through

slots in the inner and outer shells for that purpose, and which valve is thus operated externally. The walls of the shell B terminate against the inclined top and bottom of the case, except on one of the lower sides, where the wall is cut away to permit the heated currents to pass between the inner and outer shells, when compelled to take that course by the closure of the inner shell.

D is a diaphragm or stop-plate, secured to and projecting from one corner of the inner shell into the adjacent corner of the case.

E are deflecting-plates, starting from the stop-plate, and extending, horizontally, nearly around the inner shell, to which they are secured.

E' are similar plates, intermediately disposed between the plates E, but start from the opposite side of the stop-plate. Both series of plates are inclined upward, and are of such width, that when placed within the case A, they will touch its inner walls, and, with them, form alternating or zigzag flues, through which the heated currents are compelled to pass, and, as their tendency is upward, by the inclination of the plates E E', they are compelled to pass in proximity to the walls of the case, which thereby more readily take up the heat, and radiate it into the apartment.

The rectangular form is preferable to the circular, in radiators of this description, as the currents are retarded in their passage more than they would be in going around a circular shell; and I am thereby enabled to dispense with a certain number of the deflecting-plates, to make the whole of less height, and at a reduced cost.

What I claim as my invention, and desire to secure by Letters Patent, is—

1. The rectangular inner shell B, provided with valve C and lever *c*, stop-plate D, and alternating deflecting-plates E E', as and for the purpose set forth.

2. The combination and arrangement of the foregoing parts within the rectangular case A, in the manner and for the purpose specified.

GEO. W. LORE.
